UNITED STATES PATENT OFFICE.

JAMES ROBERT COE, OF ANSONIA, CONNECTICUT, ASSIGNOR TO GEORGE H. BENJAMIN, TRUSTEE, OF NEW YORK, N. Y.

GRINDING-MACHINE.

No. 832,775.

Specification of Letters Patent.

Patented Oct. 9, 1906.

Application filed February 11, 1905. Serial No. 245,280.

To all whom it may concern:

Be it known that I, JAMES ROBERT COE, a citizen of the United States, residing at Ansonia, county of New Haven, State of Connecticut, have invented certain new and useful Improvements in Grinding-Machines, of which the following is a specification.

My invention relates to grinding-machines of a type adapted as a cutting and finishing machine for metals or other materials.

As grinding was originally considered to be a rubbing or wearing-away operation in which both elements were reduced in proportion to their hardness, the grinding-machine was accordingly constructed merely to mechanically present the rubbing-body to the work to produce a superior quality of finish over that obtainable by the use of a lathe or planer. Comparatively recent developments have shown, however, that the operation is actually one of cutting, the grinding-wheel being a gang-cutter presenting millions of individual cutting-points each acting in a similar manner to a lathe-tool, and when, therefore, each cutting-point in the surface of the wheel is made to do its share of the work the aggregate removal of stock is such as to make the grinding-machine an important factor both in cutting and finishing.

The highest efficiency in cylindrical grinding is obtained when the wheel's cutting path on the work is a spiral having a pitch equal to the width of the wheel; but in practice variable conditions in size, shape, nature of material being ground, and qualities of finish desired make it impossible to invariably use a feed equal to the width of wheel, and means must therefore be provided by which an operator can adjust the feed to the immediate conditions obtaining. It is obvious that the "unit of feed" should be the width of the wheel, and as practice has proved that a single wheel suitable to the material being ground is capable of both roughing and finishing the work, provision is made in the present machine for changes of feed graduated in definite degrees of one wheel width.

As a grinding-wheel running at a fixed surface speed is capable of removing only a definite amount of material in a certain time and as the amount of surface presented to the wheel at one revolution of the work depends on the diameter of the cut it is necessary to provide means for changing the speed

of the work to suit its diameter, the depth of wheel cut and feed of work being constant. It will be readily understood that these adjustments in speed and feed to meet change in diameter of work, nature of material, and depth of work are of frequent occurrence, and it becomes of vital importance that the loss of the operator's time necessary for the same should be reduced to a minimum. With this object in view the machine embodying my invention is so designed that every adjustment is clearly defined and conveniently within reach of the operator without requiring him to leave his position at the center of the machine.

In modern grinding-machines the institution of various adjustments has led to the use of extension counter-shafting which makes the handling of heavy work very difficult, preventing, as it does, the use of mechanical lifting and overhead-carrying devices. To overcome this objection, the present machine is made entirely self-contained in its drive—that is to say, it receives power at a definite point either from belt or motor and distributes it internally to the various points of application.

In the modern application of grinding to the manufacture of all cylindrical machine parts it very often becomes necessary to "run into a shoulder," thus necessitating providing, first, micrometer means for determining exactly the point of feed-stop; second, a delayed reversal until the work makes at least one complete revolution in order to prevent leaving a portion of the surface unfinished, and, third, means for insuring against slippage in the operating parts of the reverse mechanism. To meet these conditions, I employ a timed mechanism actuated directly by the driving-shaft operating the headstock instead of through clamp-dogs attached to the table, as is the case in other machines, the action of placing the mechanism in operation being through the dogsstriking screws having micrometer adjustments and locking-nuts. The reverse mechanism is also arranged to operate the cross-feed device for determining or adjusting the cut of the wheel while the table is standing still, thus eliminating the tapering off of the ends of the work by the feeding in of the wheel before the end of the stroke, as is the case in all existing machines in which the cross-feed mechanism

is operated by the table-dogs. The cross-feed device is so arranged that the amount of feed is governed and predetermined by a graduated index, the advantage of which is 5 obvious.

Modern grinding-machines are ordinarily provided with means for operating the table-traverse by hand as well as power, and as the two have never been made distinct in their 10 action the hand-wheel is constantly revolving when the table is in operation, thus forming a menace to the safety of the operator. To avoid this, the present machine is so designed that the operation of a clutch automatically precludes the operation of the hand-wheel when the power-feed is in action, and vice versa.

Practice in grinding today includes the use of a large amount of soda-water, which acts to 20 destroy the machine-oil used to lubricate the sliding bearings unless they are protected or covered. Protecting means of various kinds have been employed in existing machines, some using an extended cover of cast-iron attached to the ends of the table, which adds to 25 the necessary floor-room required by the machine. Others use sheet-iron strips attached to the bed throughout its length and extending inwardly, requiring the table to be under- 30 cut to clear these guards, and thereby greatly weakened, or a canvas strip similar to a window-curtain, which quickly wears out, owing to its contact with the oil. For this purpose I have provided a flexible metal strip extending 35 through holes in the table and so arranged as to overcome all the aforesaid objections.

A very important feature in modern grinding is the use of back rests to prevent sag or 40 spring of the work away from the wheel. For work of fairly large diameter only single blocks are used at the back of the work, while for work of small diameter an extra piece is used carrying blocks to support the 45 work both from behind and from below. In machines now in general use such a single block is adjustable vertically and inward by independent screws, the adjustment of either of which disarranges the other. To over- 50 come this objection, I have provided means for independently adjusting the vertical blocks and the horizontal blocks in direct lines.

A machine suitable for carrying my invention into effect is illustrated in the accompanying drawings. I wish it understood, however, that I do not limit myself to the same, as various other mechanisms may be employed, operating in substantially the 55 same manner to produce practically the same result.

In the drawings, Figure 1 is a front elevation of the machine. Fig. 2 is a top or plan view. Fig. 3 is a cross-sectional view of the 60 machine, taken on the lines 3 3 of Fig. 1, show-

ing relative position of parts with largest wheel and work. Fig. 4 is a similar view taken on the line 4 4 of Fig. 1. Fig. 5 is a cross-section taken on the line 5 5 of Fig. 2. Fig. 6 is a horizontal section taken on the line 6 6 of Fig. 1. Fig. 7 is an enlarged cross-sectional view taken on line 7 7 of Fig. 1, showing the work in position. Fig. 8 is an enlarged front view of the driving mechanism, shown with parts shown in section. Fig. 9 is 75 an enlarged front view of the driving mechanism, showing a modification of the reverse mechanism. Fig. 10 is an enlarged view in the perspective of the end of the machine, showing the arrangement of way-guard. Fig. 11 is a detail view showing the relation of the grinding-wheel to the work and indicating the general direction of the cut when the feed is such as to advance the work one wheel width for each complete revolution of the 80 work. Fig. 12 is an enlarged view in section, showing one of the oil-pockets and its contained feed-roll employed in the bearings of the wheel-spindle. Fig. 13 is an enlarged detail front view of the reverse mechanism. Fig. 14 is a similar view of the same in an adjusted position. Fig. 15 is a sectional view on the line 15 15 of Fig. 14. Fig. 16 is a sectional view of the reverse mechanism, taken on the line 16 16 of Fig. 14. 95

Referring now to the drawings, the base or bed 1 is provided, as shown in Figs. 1 and 7, with ways 2, extending laterally throughout its length, forming sliding surfaces for the table 3, such ways having at intervals oil-pockets 4, in which oil-rolls 5 of familiar construction are so arranged as to operate against and supply oil to the bottom of the table. Oil-pockets 6 to receive the overflow are provided at the ends of the base, which is 100 of box form, having openings 7 in its front side to admit the various mechanisms. Immediately behind the ways and extending throughout the length of the base is a trough 8, Fig. 4, adapted to receive the water used 105 in operation and convey it back to the settling-tank 9, which is formed by a compartment in the base, as shown at the left of the wheel in Fig. 2. This settling-tank 9, as shown in Figs. 2 and 3, is separated from the 110 pump-tank 10 immediately behind it by a partition 11, over which the water flows into the pump-tank after depositing any grit it 115 may hold in the settling-tank. Underneath the settling and pump tanks, Figs. 5 and 6, 120 is a space 12, left clear for a cone-belt, and to the right is shown a compartment 13 for the wheel-driving mechanism. The compartment 13, as shown in Figs. 2, 4, and 5, is surrounded by the wheel slide-base 14, a casting having ways 15 extending throughout its 125 length at right angles to the direction of the table-ways on the base and on which the wheel-slide is carried back and forth by means of the screw 16, carried in bearings 17, 130

extending downward from the bottom of the wheel-slide base. This screw is operated through gears 18 19 by the shaft 20, extending to the front of the machine, as shown clearly in Fig. 4. The wheel-slide 21 consists of a heavy casting, having ways 22 Fig. 5, on its bottom surface corresponding to and engaging with the ways 15 on the wheel-slide base. A half-nut 23, extending downward from the bottom of the wheel-slide 21, Fig. 4, engages with the screw 16. At the front of the wheel-slide 21 are provided bearings 24 for the wheel-spindle 25. These bearings, Figs. 2 and 4, are bronze-lined and are provided with caps 26, fitted at an angle of forty-five degrees, thus presenting a solid surface to the back thrust of the wheel and the downward thrust caused by the weight of the wheel-spindle and belt-pulley. Oil is supplied to these bearings by means of oil-rolls 27, having a roughened surface carried on the swinging frames 28 in pockets 29 in the wheel-slide and extending upward through slots 30 in the bronze liners 31 to contact with the wheel-spindle 25, which contact is insured by means of spring acting against the lower side of the swinging frames, as shown in Figs. 4 and 12. The wheel-spindle 25, operating in the bearing 24 in the wheel-slide 21, is a heavy steel spindle carrying the wheel 32 on one end, having a thrust-bearing 33, Fig. 2, on the other end and a drive-pulley 34 located between the bearings.

The wheel is secured to the spindle in the usual manner and, as shown in Fig. 3, revolves in a heavy casing 35, adjustable forward and back on ways 36, Fig. 2, provided at the side of the wheel-slide to compensate for wearing down of the wheel. This casing serves the double purpose of protecting the operator from injury in case of wheel accident and of confining the water of operation from misting while being led back to the settling-tank.

As shown in Fig. 4, the wheel-spindle is driven from a jack-shaft 37 in the compartment 13 in the base by a belt 38 traveling over idler-pulleys 39, which are carried in a frame 40, Fig. 2, arranged to slide back and forward in ways 41, provided on the wheel-slide, this idler-frame being drawn toward the back of the wheel-slide by means of the heavy spring 42, Fig. 2, thus putting the necessary tension on the belt. Hinged on the wheel-slide bearing-caps 26 is shown a cover 43, Figs. 2 and 4, which extends over the belt-bulley 34 and protects the same from water. Hinged to the first cover 43 is a second cover 44, which extends down in front of the wheel-slideways 22, the operation of which is clearly shown in its extreme positions in Figs. 4 and 7. The wheel jack-shaft 37 revolves in bearings 45, Fig. 6, secured to the machine-bed, and is driven by

gears 46, 47, 48, 49, 50, and 51 from the main shaft 52.

Three changes of gear speeds are provided to compensate for the wearing down of the wheel, the object being to keep the surface speed of the wheel approximately uniform. This main shaft receives power for the entire machine from a belt running over tight and loose pulleys 53 54, as shown at the extreme right of Figs. 2 and 6. A pulley 55 at the opposite end of the main shaft, Fig. 5, drives, by means of a belt 56, running over guide-pulleys 57, a pump 58 of the well-known vertical centrifugal type commonly used on work of this character and which is carried on the perforated cover 59 to the pump-tank 10 in the bed and supplies water to the point of contact through hose 60 and pipe 61. (Shown in Figs. 2 and 3.) The main shaft 52 also carries a drum-pulley 62, Fig. 6, which drives the cone-pulley 63 on the front of the machine, by means of an endless belt 64, running over take-up idlers 65, Fig. 3, swinging on a stud 66, extending from the bed and operated by a spring 67. The cone-pulley 63 has five steps and is provided with a tapered portion 63^a, Fig. 6, between the steps to permit the shifting of the belt by means of a shipper 68, (shown in Fig. 7,) which is arranged to slide along a track or bar 69, secured to the drive-plate 70, fastened to the front of the machine and carrying the entire drive mechanism.

The cone-pulley 63 revolves the main drive-shaft 71 through a cone friction member 72, (shown clearly in Fig. 8,) the object of which is to provide a safety-point in case of accident. Immediately to the right of the cone-pulley on the main drive-shaft 71 are shown two loose clutch-pulleys 73 74, Fig. 8, each of which carries a belt 75, which, running over swinging idlers 76, Fig. 7, drive the drum 77, carried underneath the sliding table in bearings secured to the sliding table, from which in turn power is transmitted to the head-stocks, as hereinafter described. These two loose pulleys 73 74 on the main drive-shaft 71 have a diametrical ratio of one and two and are arranged so that either one can be driven by the shaft through the sliding jaw-clutch member 78, operated by means of the lever 79. (Shown clearly by Fig. 9.)

It will be clearly seen that the arrangement described gives two changes of head-stock speed—i. e., fast and slow—for each of the five speeds imparted by the cone-pulley 63 to the main drive-shaft 71, or ten head-stock speeds in all, five of which are designed to be used for finishing work, the figures shown on the cover representing the revolutions per minute that the head-stock will make when the belt is in any one of the several positions.

At the extreme right of the main drive-shaft 71, as shown in Fig. 8, is located another cone-pulley 80, which drives a corre-

sponding cone-pulley 81 on a jack-shaft 82, immediately above the main drive-shaft. The proximity of these shafts and the necessity of providing a single shipper for the belt 5 approaching both pulleys requires the use of a special drive, which is shown clearly in Fig. 4 as consisting of three idler-drums 83, 84, and 85, of width of face equal to the length of the cone-pulleys. The middle 10 idler 84, carrying the tight or pulley side of the belt 86, is carried rigidly on a stud 87, extending from the bracket 88. The upper and lower idlers are carried on a swinging frame 89, hinged on a second stud 90, extending from the bracket and operated by a tension-spring 91. The belt 86 is endless and runs in the direction indicated by the arrows approaching both pulleys through the bat-wing shipper 92, Fig. 4, which is arranged to slide on a track or bar 93, secured to the drive-plate.

As shown in Figs. 14 and 16, the second or jack shaft 82 carries two tight pinions 94 95, which engage with loose clutch-gears 96 97 25 on the worm-shaft 98, one engaging direct, the other through an intermediate 99, the relative proportions of each pinion to its gear being identical. The worm-shaft 98, as shown in Fig. 8, revolves in bearings 100, 30 forming part of a bracket 101, and carries a worm 102, running in an oil-bath 103 and engaging with a bronze worm-wheel 104, which, as shown in Fig. 7, revolves loose in a web or rim bearing 105 on a hub 106, tight to the 35 rack-pinion shaft 107. A spur-gear 108 is shown as having a similar bearing 109 on the hub 110 and as engaging with a pinion 111 and hand-wheel 111^a. Both the worm-wheel 104 and the spur-gear 108 have clutch- 40 teeth 112 cut on their inner periphery, as shown by Fig. 8, and a sliding key 113, having a bearing in the hub 110 and operated by means of a knob 114, extending to the front, is arranged to engage with either the worm- 45 gear 104 or spur-gear 108, so that only one can be coupled to the rack-pinion shaft 107 at a time. The rack-pinion shaft 107, Fig. 7, carries the rack-pinion 115, engaging with a rack 116, secured to and extending through- 50 out the length of the sliding table 3, and revolves in bearings 117, forming part of the worm-bearing bracket 101. It will be observed that for each of the five separate speeds of the main drive-shaft the jack-shaft 55 and the worm-shaft and the table have five distinct changes of speed by means of the double cones on the main and jack shafts, and the machine is so designed that these five changes of speed represent one, three-fourths, 60 one-half, one-fourth, or one-eighth of a wheel-width table travel per revolution of the head-stock when driven slow speed, enabling the operator to adjust his table to any desired feed for roughing. Moreover, inasmuch as 65 the table change is absolutely independent of

the fast and slow head-stock change—the change of head-stock speed from slow to fast for finishing being in the proportion of one to two—when the fast head-stock speed is being used the table advance per revolution automatically becomes only one-half as great, thus preventing too fast a table speed and giving the finer or smaller speeds required for finishing—namely, one-half, three-eighths, one-fourth, one-eighth, or one-sixteenth of a 70 wheel width per head-stock revolution.

The reverse mechanism is shown in two forms, the first and preferable being shown in Figs. 8 and 13 to 16 and the second, a modification, shown in Fig. 9. Both have for their 80 object to provide a delay in reversing of sufficient time for the head-stock to make at least one complete revolution irrespective of whatever table-feed may be in use, and it will be observed that in order to attain this object the timing of the delay must be made from the main drive-shaft.

Treating the two methods independently and in consecutive order, the first consists, as shown in Fig. 8, of a tight worm 118 on the 90 main drive-shaft 71, operating a worm-wheel 119, Fig. 16, which revolves loose on a quill 120 and carries with it a ratchet 121. This worm-wheel 119 is so designed that the number of revolutions of the main drive-shaft 71 95 required to cause one complete revolution of the head-stock shall also cause one-half of a revolution of the worm-wheel. Secured to the quill 120, Fig. 16, which revolves on a stud 122, extending from the drive-plate 70, 100 is a sprocket-wheel 123 at the rear end, and at the front end in consecutive order, as shown in Fig. 15, are, first, a pawl-arm 124, carrying a pawl 125, arranged to engage with the teeth of the ratchet 121 on the worm-gear 119 and held in such engagement by a spring-plunger 126, unless forcibly held from such engagement by the interference of a tail 127 on the pawl 125 with stop-pin 128, carried on slide 129, Fig. 14; second, a reverse-cam 130, having two steps 131 and 132, as shown, and, third, a stop-cam 133, which is a round disk with a notch 136 in its periphery, as shown. The slide 129, mounted in roller-bearings 137, Fig. 14, secured to the drive-plate, has an upwardly-extending yoke 138, 115 designed to engage with and operate a clutch-sleeve 139, sliding on a feather-key in the worm-shaft between the two loose clutch-gears 96 97 and so arranged that it can be in 120 engagement with only one of them at a time. This slide 129 carries two oppositely-placed spring-plungers 140 140, Fig. 15, so arranged as to engage with the reverse-cam 130. Two stop-pins 141 141 on its outer surface are arranged to engage with the stop-cam, and two stop-pins 128 128 on its inner surface engage with the tail of the ratchet-pawl 125. At its extreme upper part the slide 129 carries a 125 steel ratchet-tooth 142, Fig. 14, arranged to 130

engage with either of the two pawls 143 143, carried on studs 144, extending from the drive-plate 70. These pawls 143 have arms 145 extending up to and encircling a shipper-rod 146 (shown clearly in Fig. 13) and are designed to be moved outwardly by collars 147 on the rod and inwardly by springs 148 on the rod. The rod slides in bearings 149, provided by a bracket 150, and has at its center 5 an arm 151, extending upward and carrying at its upper extremity a hub 152, Fig. 13, into which two micrometer-screws 153 with graduated heads 154 and lock-nuts 155 are adjustably secured in such position as to normally stand in the path of the table-dogs 156, which are adjustably carried on a rod 157, extending throughout the length of the sliding table. The striker-arm 151 is held in its 15 normal upright position by means of a spring-plunger 158, Fig. 16, carried on the bearing-bracket, and is provided with a handle 159 to permit its operation by hand and also to permit its being revolved out of the path of the table-dogs 156 against the action of the 20 spring-plunger 158 when it is found desirable to "run by," thus preventing the necessity of changing the location of the dogs.

The operation of the reverse mechanism is shown in detail in Figs. 13 and 14 and is as follows: In Fig. 13 the mechanism is shown just before the reversing action takes place, and it will be observed that the slide 129 is in its extreme right-hand position, the clutch member 139 being in engagement with the 30 right-hand clutch-gear 97 and held in such engagement by the left-hand locking-pawl 143 against the action of the left-hand slide spring-plunger 140, which has been forced back by the reverse-cam 130. The worm-wheel 119 and ratchet 121 are moving constantly in the direction shown by the arrow; but the ratchet-pawl 125 is not in engagement with the ratchet, its tail 127 being in interference with the left-hand pin 128 on the 35 inside of the slide 129. The table 3 is traveling in the direction of the arrow, and the right-hand table-dog 156 is about to strike the right-hand screw 153. Fig. 14 shows the relative position of the various parts immediately after the reversing action has taken place, and it will be observed that the right-hand table-dog 156 has struck the shipper-rod 146, which in turn has lifted the left-hand locking-pawl 143. The left-hand slide 40 spring-plunger 140 has at once acted and forced the slide 129 to the left until the right-hand stop-pin 141 on the front of the slide engaged with the stop-cam 133 and stopped the motion of the slide 129 and the clutch member 139 in a central position, thus stopping the table-feed. This same left-hand motion of the slide 129 has drawn the interfering pin 128 out of engagement with the 45 ratchet-pawl 125, and the spring has forced 50 the pawl 125 into engagement with the ratchet-teeth 121, thus causing the revolution of the quill 120 with both the cams 130 133 and the sprocket-wheel 123. This revolution continues until the second step of the reverse-cam 130 strikes the left-hand slide 55 70 spring-plunger 140 and compresses it until the notch in the stop-cam 133 passes by the right-hand stop-pin 141 on the slide 129. Then the left-hand spring-plunger 140 again acts and causes a second motion of the slide 75 124 and clutch member 139 to the left, thus causing the reverse in the direction of the table travel. This second movement of the slide, moreover, permits the right-hand locking-pawl 141 to engage the tooth 142 on the 80 top of the slide 129 and at the same time brings the right-hand interference-pin 128 on the inside of the slide 129 into the path of the tail 127 on the revolving pawl 125. The revolution continues enough farther to permit the 85 reverse-cam 130 to compress the right-hand slide spring-plunger 140, and the ratchet-pawl 125 then pulls itself out of engagement by the tail 127, and the mechanism is again 90 in working order.

The second form of reverse mechanism, as shown in Fig. 9, consists of a worm 118^a, loose on the main drive-shaft 71, having clutch-teeth on either end. This worm engages a worm-wheel 119^a, which revolves 95 loose on a stud 122^a, extending from the drive-plate 70, and carries with it, first, a reverse-cam 130^a, which is a round disk having a spring-plunger 138^a extending out through its periphery and a notch 131^a in its periphery directly opposite its plunger 138^a; second, a stop-cam 133^a, which is a round disk having a pin extending from its periphery, and, third, a sprocket-wheel 123.

Two primary levers 143^a are hinged on 105 studs 142^a, extending from the plate 70, having contact-points 139^a at their upper ends, adapted to engage with the stop-cam 133^a, and also notches 140^a, arranged to engage with the locking-pawls 141^a, which are shown 110 as suspended from a bell-crank 149^a through bearings 147^a on the drive-plate 70. At their lower ends the primary levers 143^a are held apart by a heavy compression-spring 146^a and are designed to engage with and operate 115 two clutch members 137^b, sliding on feather-keys in the main drive-shaft 71 and arranged to engage with the clutch-teeth on either end of the loose worm. Two secondary levers 143^b, also hinged on the same studs as the 120 primary levers 143^a, have contact-points arranged to engage with the reverse-cam 130^a and at their upper ends are secured to a shipper-rod 144^a, having a yoke 136^a, designed to engage with and operate the clutch member 125 137^a, sliding on the worm-shaft 98, between the loose clutch-gears 96 97. The table-dogs 156^a are provided with adjustable micrometer-screws 151^a, carried on a hinged piece arranged to normally lie in such position as 130

to interfere with the striker-arm of the bell-crank 149^a, but capable of being lifted to a clearing position. The mechanism is shown just as the reversing action is about to take place, and it will be observed that both the primary levers 143^a are in a restrained position and held in such a position by the locking-pawl 141^a. Consequently both clutch members 137^b are out of engagement with the worm 118^a on the main drive-shaft 71, and it is standing still. Moreover, the left-hand secondary lever 143^b is in the notch in the reverse-cam 130^a and held there by the action of the spring-plunger 138^a against the right-hand secondary lever 143^b, and the clutch member 137^a is consequently in engagement with the right-hand loose clutch-gear 97, and the table is traveling in the direction shown by the arrow. The left-hand table-dog 156^a is, however, in contact with the striker-arm of the bell-crank 149^a, and the left-hand locking-pawl 141^a is about to release the left-hand primary lever 143^a. As soon as this release occurs the compression-spring 146^a will 25 act, forcing the primary lever 143^a in toward the center, thus entering the left-hand clutch member 137^b into engagement with the clutch-teeth on the left-hand end of the worm 118^a and causing rotation of the same. As 30 soon as this rotation commences the reverse-cam 130^a will force the left-hand secondary lever 143^b out of the notch in its periphery and the upper clutch 137^a will assume a central position, thus stopping the table-feed. 35 This delay will continue while the worm-wheel 119^a and cams continue to revolve until they have made a half-revolution, in which time the head-stock will have made at least one complete revolution. When the 40 spring-plunger 138^a in the reverse-cam 130^a strikes the left-hand secondary lever 143^b, it will be compressed until the notch in the reverse-cam passes the contact-point of the right-hand secondary lever 143^b, when it will 45 immediately act and force the upper clutch member 137^a into a left-hand position, causing the reverse in the table motion. The further rotation of the worm-wheel and cams brings the projecting pin 139^a in the periphery 50 of the stop-cam 133^a into engagement with the left-hand primary lever 143^a, thus forcing out the lower left-hand clutch 137^b and stopping further revolution of the worm 118^a. In either case it will be observed that 55 the sprocket-wheel 123, secured to the cams, makes one-half a revolution every time the motion of the table is reversed, and the said half-revolution takes place while the table is standing still. This sprocket 123 is arranged, 60 as shown in Figs. 8 and 16, to drive, by means of a chain 158, a second sprocket 159, whose diametrical ratio to the first is as one to two. Hence the second sprocket will make a complete revolution when the reverse occurs. This second sprocket is arranged, as

shown in Figs. 8 and 16, to revolve a crank-disk 160 through a spring-pin 161, capable of being withdrawn when it is not desired to use the automatic cross-feed. The bell-crank 162 carries on one arm a spring-pawl 163, arranged to engage with the teeth of a spur-gear 164, tight on the wheel feed-shaft 20, the design of the machine being such that each tooth in the periphery of the gear represents a wheel advance of one one-thousandth of an inch, as shown clearly in Fig. 8. A shoe 166 is also hinged on the wheel feed-shaft in such a manner as to hold the pawl out of engagement during any desired part of its reciprocation, and this shoe, having a spring-pin 167, Fig. 9, engaging with numbered holes 168 in the cover 169, enables the operator to adjust the feed to any predetermined number of one one-thousandths required. Engaging with the spur-gear 164 is a pinion 170, 85 carrying a hand-wheel 171, the periphery of which is graduated, thus providing suitable means for manually advancing or backing of the wheel.

The sliding table 3 is provided with ways 90 on its lower surface corresponding to and engaging with the ways on the machine-bed, as above described. The table-rack 116 (shown in Figs. 7 and 8) is also secured to the lower side of the sliding table and extends throughout its length, as does the head-stock drum 77, which revolves in self-oiling bearings secured to the sliding table. On its front edge is carried the rod 157, Fig. 1, along which the table-dogs 156 are adjustable. At either 100 end of the sliding table is a clamp 172, arranged to hold down the swivel-table 3^a, the right-hand clamp being provided with a binding-screw and handle 173. (Shown clearly in Fig. 1.) Extending throughout the length 105 of the sliding table immediately over each way are provided rectangular holes or chambers, through which are arranged to operate the bed water-guards 174. (Shown in Fig. 10.) Each of these guards consists of two 110 strips 175 of thin flexible sheet metal joined together by means of a spiral spring 176, the whole guard in a normal condition being the same length as the bed. These guards are arranged to operate through the slots 177 in 115 the sliding table, passing under the guide-rolls 178, shown at the ends of the table, and are connected together at their extremities by means of a round rod 179. Yoke-pieces 180, provided on the ends of the bed, are 120 adapted to engage with the ends of these rods 179 when the table passes in from the end of the bed, thus causing a stretching of the spring members of the guards. Yokes 181 are also provided on the ends of the sliding table to support the rod when the table passes out away from the end of the bed, as 125 shown clearly by Fig. 10. The swivel-table 3^a is arranged to rest on the top of the sliding table, to which it is held at its center by 130

means of a pivot 182, entering both tables, (shown by Fig. 7,) which construction permits of a rotation or swiveling of the swivel-table 3^a about the pivot in a horizontal plane 5 on the sliding table 3, this rotation being governed by means of a screw 183, carried by the swivel-table, engaging with a nut 184, carried by the sliding table, as shown by Figs. 1 and 4. On its upper surface the swivel-table is 15 provided with ways 185, along which the head-stock 186 and foot-stock 187 are adjustably secured by means of binding-bolts 188, the heads of which engage with a slot 189, provided in the upper side of the swivel-table 20 for this purpose.

Carried in brackets 190 on the ends of the swivel-table 3^a is a shaft 191, extending throughout the length of the table and located over the front way, as shown in Figs. 3 20 and 7. This shaft 191, Fig. 3, is revolved by means of a belt 192, driven by the drum 77, carried on the lower side of the sliding table and running over take-up guide-pulleys 193, carried on a frame 194, attached to the end of 25 the swivel-table. The shaft 191 has for its object the revolution of the head-stock drive-plate by means of a pinion 195, carried by the shaft in such a manner as to be capable of lateral motion with the head-stock, and an intermediate pinion 196, engaging with the first pinion 195 and with a large spur-gear 197, arranged to revolve about the head-stock dead-center 198 and carrying the head-stock drive-plate 199, to which are secured the work 30 drive pins or dogs 200. The head and foot stocks are of familiar type common to this class of machinery and need no description. They are both adjustable in and out from the center of the swivel-table, their working position when determined to suit the length of 35 the work being secured by means of binding-bolts and handles 201, as shown by Figs. 2, 3, and 4.

The back-rests 202 (shown by Figs. 1 and 45 7) are arranged to be carried on the swivel-table, to which they are secured by means of a swinging clamp 203 and binding-screw 204 and consist of a box 205, having a hinged cover 206, provided with a clamping-screw 50 207 and having on its front side an adjusting-screw 208, designed to operate against a single wooden or babbitt block 209, which in turn supports the work 210. When the work is of small diameter, it is necessary to 55 support it from below, as well as from the direct thrust of the wheel, toward the front of the machine. For this purpose a special frame 211, known as a "universal back-rest," is arranged to be removably carried in the 60 primary box, to which it is secured by dowel-pins, as shown, and is also designed to have a support bearing on the swivel-table itself. The frame 211 is provided with a vertical way 212, on which the vertical block 213 is

adjustable by means of a screw 214 and hand-knob 215, as shown.

The operation of the machine described briefly is as follows: The operator selects a wheel suitable for the nature of material of the piece of work to be ground and secures 70 the same to the wheel-spindle, having removed the wheel-guard or casing-cover to permit access to the same. He then adjusts the head and foot stocks to such a position as will bring the work approximately in the center of the machine and adjusts the back-rests to properly support the work, using the single block-supports if the work is of large diameter or of comparatively short length in relation to its diameter, or using the universal-back-rest frames if the work is of small diameter. He next adjusts his table-dogs to give the requisite table travel and observes as to whether the swivel-table is properly set to grind straight or tapering, as the 80 case may be. He next adjusts the speed-change gears at the back of the machine to suit the diameter of the wheel he may be using and starts the machine in operation. With the machine in operation his first duty 85 is to see that the wheel is running true, and if not to "dress it" by means of a diamond-tool. He then determines what speed of the head-stock he requires for the particular diameter of the work he happens to have to do 90 and makes his adjustment for the same. For example, if the work were of as large diameter as the machine could swing he would use the slowest speed possible. His next operation is to bring the wheel up to the work and open 95 the water-valve on the pump-line and so direct the flow as to strike the contact-point between wheel and work. He will then adjust his wheel-feed to the greatest practical depth of cut and adjust his table-feed to 100 the greatest practical degree of the unit, one wheel width per revolution of the head-stock, and proceed to rough down the work, the spiral cut produced by the wheel upon the work being indicated by dotted lines in Fig. 110 11. If a considerable amount of stock is to be removed, he, having determined how many thousandths of an inch can practically be removed at each cut, will set the automatic cross-feed at that point, and he can 115 then devote his entire attention to the manipulation of the back-rest-adjusting screws, which, of course, have to be continually adjusted as the work decreases in diameter. Having roughed the work down within a 120 small limit of the desired size, his next operation is to throw in the fast speed of head-stock, reduce the depth of cut, and adjust the table-feed to such a degree as will give the desired finish, and in event of enough roughing-work having been done to roughen the 125 surface of the wheel before taking the last cut he will "run his table by" and dress the

wheel by means of a diamond-tool supported by the foot-stock.

I claim—

1. A grinding-machine, comprising a rotary cutter, supporting means for the work, means for adjusting the cutter and the work relatively to each other, means for giving the work rotary and longitudinal feed and graduated means for uniformly varying the speed 10 of rotation of the work.

2. A grinding-machine, comprising a rotary cutter, supporting means for the work, means for adjusting the cutter and the work relatively to each other, means for giving the 15 work rotary and longitudinal feed and means whereby the longitudinal feed and rotary feed are given a definite relation.

3. A grinding-machine, comprising a rotary cutter, supporting means for the work, 20 means for adjusting the cutter and the work relatively to each other, means for giving the work rotary and longitudinal feed and means whereby the longitudinal feed and rotary feed are given a definite changeable relation.

25 4. A grinding-machine, comprising a rotary cutter, supporting means for the work, means for adjusting the cutter and the work relatively to each other, means for giving the work rotary and longitudinal feed and means 30 whereby the longitudinal feed and rotary feed are given a graduated definite changeable relation.

35 5. A grinding-machine, comprising a rotary cutter, supporting means for the work, means for adjusting the cutter and the work relatively to each other, means for giving the work rotary and longitudinal feed and means 40 whereby the longitudinal feed and rotary feed are given a definite changeable relation graduated in terms of one wheel width.

45 6. A grinding-machine, comprising a rotary cutter, supporting means for the work, means for adjusting the cutter and the work relatively to each other, means for giving the work rotary and longitudinal feed, means for automatically reversing the longitudinal feed, and means for automatically stopping the longitudinal feed on each reversal for a 50 time sufficient for the work to rotate through a definite number of degrees.

55 7. A grinding-machine, comprising a rotary cutter, supporting means for the work, gearing for driving the cutter, means for varying the speed of rotation of the cutter, cross-feed mechanism for advancing the cutter, means for giving the work rotary and longitudinal feed, means for automatically reversing the longitudinal feed, and means for automatically stopping the longitudinal 60 feed on each reversal for a time sufficient for the work to rotate through a definite number of degrees.

65 8. A grinding-machine, comprising a rotary cutter, supporting means for the work, means for rotating the cutter and work at

relative speeds, longitudinal feed mechanism for the work, means for automatically reversing the feed at predetermined points, and means for retarding the action of the reversing mechanism to stop the feed and permit the work to rotate through a complete revolution. 70

9. A grinding-machine, comprising a rotary cutter, supporting means for the work, means for rotating the cutter and work at 75 relative speeds, longitudinal feed mechanism for the work, means for automatically reversing the feed at predetermined points, said reversing means consisting of requisite clutches, locking-dogs for the movable clutch members, and adjustable trips for the locking-dogs, together with means for automatically disengaging the clutches to stop the feed and permit the work to rotate through a complete revolution on each reversal of the 80 feed. 85

10. A grinding-machine, comprising a rotary cutter, supporting means for the work, means for rotating the cutter and work at relative speeds, longitudinal feed mechanism 90 for the work, means for automatically reversing the feed at predetermined points, said reversing means consisting of requisite clutches, locking-dogs for the movable clutch members, and adjustable trips for the locking-dogs, together with means operating to disengage the clutches, and timed cams acting through said last-mentioned means to control the reengagement of the clutches. 95

11. A grinding-machine, comprising a rotary cutter, a work-supporting table, means for rotating the cutter and work at relative speeds, longitudinal feed mechanism for the table, means for automatically reversing the feed at predetermined points, said reversing 100 means consisting of requisite clutches, locking-dogs for the movable clutch members, and adjustable trips carried by the table cooperating with the locking-dogs, together with a clutch-shifter spring actuated to disengage the clutches, and timed cams controlling the adjustment of the shifter. 105

12. A grinding-machine, comprising a rotary cutter, a work-supporting table, means for rotating the cutter and work at relative 110 speeds, continuous-feed mechanism co-operating with the table, means for reversing the table-feed at predetermined points, means for advancing the cutter to the work by hand, and means for advancing the cutter to the work by power independent of the table-feed. 115

13. A grinding-machine, comprising a rotary cutter, a work-supporting table, means for rotating the cutter and work at relative 120 speeds, continuous-feed mechanism co-operating with the table, means for reversing the table-feed at predetermined points, means for advancing the cutter to the work by hand, means for advancing the cutter to the work 125 by power independent of the table-feed. 130

- by power, independent of the table-feed, and means to predetermine the amount of such advance. 60
14. A grinding-machine, comprising a rotary cutter, a work-supporting table, means for rotating the cutter and work at relative speeds, continuous-feed mechanism coöperating with the table, means for reversing the table-feed at predetermined points, means for advancing the cutter to the work by hand, means for advancing the cutter to the work by power, independent of the table-feed, and graduated means to predetermine the amount of such advance. 65
15. A grinding-machine, comprising a rotary cutter, a work-supporting table, means for rotating the cutter and work at relative speeds, continuous-feed mechanism coöperating with the table, means for reversing the table-feed at predetermined points, means for automatically stopping the table-feed on each reversal for a time sufficient for the work to rotate through at least a complete revolution, means for advancing the cutter to the work by hand, means for advancing the cutter to the work by power while the table-feed is stopped during reversal. 70
16. A grinding-machine, comprising a rotary cutter, a work-supporting table, means for rotating the cutter and work at relative speeds, continuous-feed mechanism coöperating with the table, means for reversing the table-feed at predetermined points, means for automatically stopping the table-feed on each reversal for a time sufficient for the work to rotate through at least a complete revolution, means for advancing the cutter to the work by hand, means for advancing the cutter to the work by power while the table-feed is stopped during reversal and means to predetermine and govern the amount of such advance. 75
17. A grinding-machine, comprising a rotary cutter, a table movable in a direction parallel to the axis of the cutter, supporting means on the table for the work, changeable-speed gearing connected to rotate the work, longitudinal-feed mechanism for the table, means for automatically reversing the table-feed and means for automatically stopping the table-feed on each reversal for a time sufficient for the work to rotate through a complete revolution. 80
18. A grinding-machine, comprising a rotary cutter, a table movable in a direction parallel to the axis on the cutter, supporting means on the table for the work, cross-feed mechanism for the cutter, longitudinal-feed 85
- mechanism for the table, means for rotating the cutter and work at relative speeds means for changing the speeds, means for automatically reversing the table-feed and means for stopping the table-feed on each reversal for a time sufficient for the work to rotate through a complete revolution. 90
19. A grinding-machine, comprising a rotary cutter, a work-supporting table, means for rotating the cutter and work, means for giving the table longitudinal feed by hand, means for operating the table-feed by power and means whereby the operation of the hand-feed and power-feed is automatically made independent. 95
20. A grinding-machine comprising a rotary cutter, a work-supporting table, supporting means on the table for the work, said supporting means consisting of a frame having bearing portions independently movable thereon in direct lines vertically and horizontally relatively to the work. 100
21. A grinding-machine, comprising a bed provided with ways, guards covering the ways, a sliding table on the bed and means for providing clearance between the guards and ways for the table in its travel. 105
22. A grinding-machine, comprising a bed provided with ways, flexible guards covering the ways, a sliding table on the bed and means for raising and lowering the guards to provide clearance for the table in its travel. 110
23. A grinding-machine, comprising a bed provided with ways, flexible strips serving as guards for the ways, a sliding table upon the bed, said table being provided with openings above the plane of the ways through which the guards pass and means in advance of the table for holding the guards down upon the ways. 115
24. A grinding-machine, comprising a bed provided with ways having requisite oil-pockets, flexible strips serving as guards for the ways, springs secured to the guards, at one end thereof, a support for the opposite end of the guards, sliding table upon the bed, means for raising and lowering the guards to provide clearance for the table in its travel, and means on the table for engaging the guard-support and moving the guards against the action of their springs. 120

In testimony whereof I affix my signature in the presence of two witnesses.
